ELECTRON MULTIPLIER

Eberhard Steudel, Berlin-Dahlem, and Richard Orthuber, Berlin, Germany, assignors to Allgemeine Elektricitäts-Gesellschaft, Berlin, Germany

Application February 15, 1937, Serial No. 125,824
In Germany February 26, 1936

3 Claims. (Cl. 250—174)

There are known secondary electron multipliers, especially for the amplification of photo-currents, in the form of photo-tubes in which, besides a photo-cathode, also one or several secondary cathodes are provided which are intended to emit secondary electrons. The output of such a photo-tube depends upon the original output of the photo-cathode as regards primary electrons, as well as on the probability as to whether or not the secondary cathodes are hit by the dispersed electron- or light-rays.

The present invention relates to an arrangement in which said output is particularly great. According to this invention, the cathode consists of a tuft of threads which all at the same time serve for the primary and the secondary emission of electrons.

The invention is illustrated diagrammatically and by way of example on the accompanying drawing on which is shown an arrangement and combination of parts designed according to this invention. Figure 1 shows the entire arrangement, Figure 2 certain details thereof drawn to an enlarged scale relatively to Fig. 1.

The numeral 1 (Fig. 1) denotes the rays of light which fall on a tuft of threads 2 consisting, for instance, of glass and being covered with a substance, for instance caesium, able to emit amply a light-electric and a secondary emission; these threads are supported on a member 3. The threads 2 and said member 3 constitute together a cathode which is surrounded rotationally-symmetrically with a cylindrical anode 4. Between the cathode 2, 3 and the anode 4 lies a source of potential 5 which delivers the current that is to be measured with the aid of a measuring instrument 6.

In order to enable the primary electrons released in the cathode to release secondary electrons certain portions of the cathode must lie on a more positive material than other portions. Therefore, several cathode leads 7, 8, 9 (Fig. 2) are provided, of which the most negative one (7) leads to the middle portion of the cathode, the most positive one (9) leads, however, to the rim of the same. The supporting member 3 consists of an insulating substance into which are embedded several conducting rings or the like 10, each of which contains a tuft of threads. The conducting tuft-bearing members 10 are connected with the leads 7, 8 and 9, so that, therefore, the middle tuft is that which is most negative and the light-electric electrons released in it are able to release secondary electrons at the outer tufts. Just so, the light-electric or secondary electrons released in the tuft with the lead 8 are able to release secondary electrons also at the most outwardly located tufts.

Primary and secondary electrons are drawn onto the anode cylinder by the field of the same. If the bearing members 10 are designed as rings, one of the leads 8 and one of the leads 9 can be saved.

With such an arrangement as constitutes the present invention a particularly great output as regards secondary electrons is attained, in that, firstly, the entire surface of the cathode is very large and delivers, therefore, a considerable amount of primary electron emission, secondly, the entire large cathode surface is utilised at the same time for the secondary emission, and thirdly, owing to the electric field being directed perpendicularly to the tufts and radially, a very great probability is established that the tufts are hit by electrons emitting secondary electrons.

The secondary electron multiplier designed according to this invention is suited not only for use as a photo-tube, but can be employed also as multiplier for another radiation, for instance for cathode rays, if a suitable aperture for the entrance of these rays, for instance a Lenard-window, is provided.

We claim:

1. An electronic multiplier tube comprising an anode member, a composite electrode centrally positioned relative thereto comprising a plurality of separate tufts of electron emissive thread-like members, and means individually insulating the separate tufts, each tuft having a lead connected thereto whereby they may be maintained at different negative potentials with respect to said anode member.

2. An electron tube comprising a ring-like anode, a composite electrode centrally located relative thereto comprising a plurality of mutually insulated tufts of electron emissive thread-like members, and leads connected thereto whereby said tufts are adapted to be maintained at potentials increasing in a negative sense relative to the anode in accordance with the radial distance to each tuft from said anode in order that each may emit primary and secondary electrons simultaneously.

3. An electronic multiplier device comprising a cylindrical anode member, an electrode mount positioned internally of the anode member and symmetrically located relative thereto, said mount comprising an insulated member and a plurality of individual tufts of electron emissive elements supported within the insulating material, and conducting elements supported by the insulating material and individually connected to the separate tufts of the electron emissive elements.
